UNITED STATES PATENT OFFICE

INGVALD RUND, OF HAYTI, SOUTH DAKOTA

ELEVATOR LIFTING MECHANISM FOR GRADERS

Application filed September 11, 1931. Serial No. 562,391.

This invention relates to elevator lifting mechanism for graders.

The primary object of the invention is to provide a mechanism applicable for use in lifting jointed elevators of graders.

A further object of the invention is to provide a mechanism of such class which is positively driven from the drive shaft for the elevator.

10 A further object of the invention is to provide such mechanism which is of simple and inexpensive construction, and which may be readily assembled with respect to conventional graders now in common use.

15 With the foregoing and other objects in view, the invention consists of such parts and combinations of parts as are set forth in the appended claims.

20 In the accompanying drawings:

Figure 1 is an elevation illustrating a lifting mechanism in accordance with this invention in applied position.

Figure 2 is a top plan thereof.

25 Figure 3 is an enlarged sectional elevation taken at a plane indicated by the line 3-3 of Figure 2.

Figure 4 is an enlarged sectional elevation taken at a plane indicated by the line 4-4 of Figure 2.

30 Referring to the drawings in detail, the numerals 1 and 2 respectively indicate the upper and lower sections of a jointed elevator operated by means of a chain 3 from a drive shaft 4. The drive shaft 4 is suitably mounted in the frame 5 of the grader indicated generally at 6.

35 The upper section 1 may be lifted by the rotation of a shaft 7 which is journaled in the frame 5 and operatively connected with the section 1 by means of a pair of chains or cables 8. Each of the chains 8 is secured at one end to the frame 5, and passes around a pulley 9 secured to the section 1 by a strap 10, then passes over a pulley 11 mounted on the frame 5 and is secured at its opposite end to a drum 12 fixedly mounted on the shaft 7. Obviously upon the rotation of the shaft 7, the section 1 will be raised by the chains or cables 8.

40 The lower section 2 may be lifted by the

rotation of a shaft 13 which is journaled in the frame 5 and operatively connected with the section 2 by means of a pair of gears 14 and a pair of racks 15. The gears 14 are fixedly mounted on the shaft 13 and mesh with the teeth of the racks 15 which are fixedly secured at their lower ends to the section 2. Obviously the section 2 and racks 15 will be lifted bodily upon rotation of the shaft 13 in a counter clockwise direction as viewed in Figures 1 and 3.

45 Fixedly mounted on the drive shaft 4 is a clutch element 16 for engagement by a pair of oppositely disposed clutch members 17 and 18 respectively formed integrally with sleeves 19 and 20 rotatably mounted on the drive shaft 4. Fixedly mounted on sleeve 20 is a sprocket 21 which drives a chain 22 extending around the same and around a sprocket 23 fixedly mounted on a shaft 24 journaled in the frame 5. Fixed to the sprocket 23 is a gear 25 which meshes with a gear 26 of the shaft 13 for rotating the latter. The clutch member 18 may be engaged when desired by means of a lever 27 pivotally connected intermediate its ends to the frame 5. Having one end pivotally connected to one end of the lever 27 is a push bar 28, the opposite end of which is forked for engagement with a grooved collar 29 formed on the sleeve 20.

50 Fixedly mounted on the sleeve 19 is a sprocket 30 which drives a chain 31 extending around the same and around a sprocket 32 fixedly mounted on a shaft 33 journaled in the frame 5. Mounted on the shaft 33 is a gear 34 which meshes with a gear 35 on the shaft 7 for rotating the latter. The clutch member 17 may be engaged when desired by means of a lever 36 having one end pivotally connected to the frame 5. Having one end pivotally connected with the lever 36 is a pull bar 37, the opposite end of which is forked for engagement with a grooved collar 38 formed on the sleeve 19.

55 It is to be understood that the embodiment of the invention herein illustrated and described is to be considered as a preferred example of the same, and that changes in the details of construction may be made, so

long as such changes fall within the scope of the appended claims.

I claim:

- 5 1. In a lifting mechanism for a grader having an elevator driven from a drive shaft and including upper and lower sections, a clutch element fixedly mounted on the drive shaft, a pair of clutch members slidably and rotatably mounted on the drive shaft, shifting means for engaging the clutch members with the clutch element, and means operatively connecting said clutch members with said sections to provide for the lifting of the latter upon the engagement of the 15 clutch members.
- 10 2. In a lifting mechanism for a grader having an elevator driven from a drive shaft, a clutch element fixedly mounted on the drive shaft, a sleeve slidably and rotatably mounted on the drive shaft and having a clutch member for engagement with said clutch element, shifting means for engaging the clutch member with the clutch element for rotating said sleeve, a sprocket rotatable with said sleeve, a rack secured to said elevator and projecting upwardly therefrom, a rotatable gear meshing with said rack, and means operatively connecting said gear with said sprocket for rotating the gear to lift the elevator upon 30 rotation of the sleeve.
- 15 3. In a lifting mechanism for a grader comprising in combination, an upstanding frame, an elevator extended from the latter, a drive shaft journaled in the bottom of the frame and operatively connected to the elevator for operating the latter, a clutch element fixedly mounted on the drive shaft, a sleeve slidably and rotatably mounted on the drive shaft and having a clutch member for engagement with said clutch element, shifting means for engaging the clutch member with the clutch element for rotating said sleeve, a sprocket rotatable with said sleeve, an upper shaft journaled in the top of the frame and 40 provided with a gear, a strap secured to said elevator, a pulley secured to said strap, a cable extending around said pulley and having its respective ends secured to the frame and to the upper shaft, and means at and 45 depending from the top of the frame for operatively connecting said sprocket with said gear rotating such upper shaft to lift the elevator upon rotation of said sleeve.
- 50 4. A lifting mechanism for a grader, comprising in combination, an upstanding frame, an elevator extended from the latter and formed of a pair of jointed sections, a drive shaft journaled in the bottom of the frame, a clutch element fixedly mounted on said shaft, a pair of lifting elements for the sections of the elevator, one attached to one section and the other attached to the other section of the elevator, means mounted at the top of the frame for operating one of said lifting elements, means supported by the frame below 55
- 60
- 65

the top thereof for operating the other of said lifting elements, a normally inactive drive connection between the upper of said means and said drive shaft, a normally inactive drive connection between said lower means and the drive shaft, and means for selectively clutching said drive connections to the drive shaft to selectively make active one of said drive connections.

In testimony whereof, I affix my signature 75 hereto.

INGVALD RUND.
